(57) **CLAIM**

What is claimed is the ornamental design for a cloth accessory with a closable flap, as shown and described.

DESCRIPTION

FIG. 1 is a bottom left perspective view of the invention with a flap portion closed;

FIG. 2 is a bottom left perspective view of the invention with a flap portion open;

FIG. 3 is a front view thereof;

FIG. 4 is a rear view thereof;

FIG. 5 is a right side view thereof;

FIG. 6 is a bottom view thereof with a flap portion closed;

FIG. 7 is a bottom view thereof with a flap portion open;

FIG. 8 is a top view thereof with a flap portion closed;

FIG. 9 is a top view thereof with a flap portion open; and,

FIG. 10 is a bottom left perspective view of the invention with a flap portion open showing a cloth attached to the interior thereof extending out of the opening.

The phantom or broken line showing is for illustrative purposes only and forms no part of the claimed design.

The right and left sides of the device are mirror images of one another.
